John M. van Heusen
Inventor

By his Attorney

Patented Nov. 29, 1927.

UNITED STATES PATENT OFFICE.

JOHN M. VAN HEUSEN, OF BOSTON, MASSACHUSETTS.

SHOULDER STRAP.

Application filed August 2, 1924. Serial No. 729,681.

The present invention relates to improvements in shoulder straps and more particularly to shoulder straps commonly used in ladies' undergarments.

It has long been a serious objection to lingerie shoulder straps that they constantly slip from the shoulder. Furthermore, when worn a short time they wrinkle and roll up, thus taking on a "stringy" and untidy appearance.

It is one of the main objects of my invention to provide a shoulder strap which, while possessing the soft and delicate appearance and feel requisite to feminine attire of this nature, nevertheless is of such construction that it will not wrinkle or become "stringy". Another object of my invention is to provide a shoulder strap which will not slip from the shoulder under ordinary conditions of wear. Other objects will herein-after appear.

The invention will be further described in connection with the accompanying drawings illustrative of certain embodiments thereof in which,

Fig. 1 shows the shoulder straps of my invention in use.

Fig. 2 is an enlarged sectional view taken along the line 2—2 of Fig. 1, showing conventionally the fabric of the shoulder strap.

Fig. 3 shows a complete detached shoulder strap, and

Fig. 4 shows a complete detached shoulder strap of modified construction.

The fabric of which the shoulder straps of my invention are made is a pile fabric or fabric having similar properties. The particular structure and weave of the fabric may vary widely. So also any suitable material may be used in making the straps such, for example, as silk, linen, cotton, etc. I prefer to use silk throughout, as it gives a very soft, fine pile surface and a smooth attractive back, especially suitable for use in ladies' underthings of high quality. A mixture of cotton and silk may be used to reduce the cost of the shoulder straps and still retain in large measure the attractive appearance.

In the preferred embodiment of my invention the pile fabric of which the shoulder straps are made is so woven or, after weaving, is so treated as to have all the pile threads 2 inclined or slanted in substantially the same direction as shown in Fig. 2. The

direction in which the pile threads are inclined will be such that when the strap or ribbon is placed over the shoulder the pile threads will be pointing substantially in the direction of the normal slip of the shoulder straps.

While, as I have said, the shoulder straps of my invention may be produced in a variety of ways, I shall for purposes of illustration merely and not with the intention of limiting my invention in any respect, describe one way in which I produce these shoulder straps.

I weave a narrow ribbon of silk pile fabric by what is known to those skilled in the art as a "four pick pile weave". This fabric has the pile threads extending substantially at right angles to the plane of the fabric. I then moisten the pile fabric slightly with water and allow steam to play on the said pile surface. I then brush the pile face in the direction in which I desire to have the pile threads slant, at the same time steaming the fabric on the back face thereof. The fabric is then dried with the back face against a drying can. Thus treated, the fabric is provided with a pile surface of which all the pile threads are inclined in the same direction and at substantially the same angle to the plane of the fabric.

The ribbon when woven is in one continuous piece and it may be cut into desired lengths either before or after the steaming and brushing treatment above described. The cut ends of the straps may be suitably bound to present a neat appearance and prevent fraying.

The shoulder straps when worn are placed with the pile surface undermost, that is, in contact with the skin of the wearer or with an intermediate layer of clothing if there be one. At the point where the strap passes over the shoulder the pile threads are directed downwardly and outwardly towards the tip of the shoulder. This is illustrated diagrammatically at 2 in Fig. 2, which is a sectional view of the shoulder strap of Fig. 1. It will be apparent from this that any tendency of the shoulder straps to slip down and off the shoulder will be resisted by the many pile thread ends which are braced, as it were, against travel in the direction of slip. And as the strain on the strap becomes greater, increasing the tendency to slip, the restraining action of the pile surface be-

comes proportionately greater. The firmer the pressure of the strap against the shoulder, the tighter becomes the hold of the pile threads.

5 I have found that with the movement of the arms and shoulders of the wearer, the shoulder straps of my invention tend to work upward towards the wearer's neck. This action is not sufficiently positive to cause 10 inconvenience or discomfort but is a further protection against displacement of the straps.

The fabric of my shoulder strap while sufficiently soft and pliable to be of the utmost comfort and satisfaction to the wearer, is 15 possessed of a greater degree of body and firmness than the ordinary shoulder straps now used. This characteristic of my shoulder strap is an essential part of my invention and is of great importance since it tends 20 to prevent the strap from taking on, after a short period of wear, the wrinkly, "stringy" appearance which is an attribute, so far as I am aware, of all shoulder straps now in use. My shoulder strap lies flat and smooth 25 against the wearer and presents the maximum of neatness and dressiness in appearance.

My shoulder straps may be permanently 30 secured to articles of attire at the time of their manufacture or they may be made and sold separately to be secured to the garment by the purchaser. Fig. 3 shows a detached shoulder strap complete. As shown in the 35 figure, the strap may, if desired, be provided with suitable lingerie clasps or pins 3 for securing to the garment.

As the action of the pile threads in resisting slippage of the shoulder strap is most effective at the top of the shoulder where 40 the strap passes therover, and as at this point most of the wrinkling of these straps commences, it may be found desirable in some instances to utilize ordinary silk or cotton shoulder straps and provide the same at 45 the desired point with an insert of the pile fabric herein described. The insert will be so placed as to fall at the top of the shoulder and thus the advantages of my invention are, to a certain degree at least, enjoyed without using the fabric throughout. Fig. 4 50 shows a shoulder strap 4 of this sort, the shaded portion 5 representing the pile fabric insert.

55 My shoulder straps may, of course, be made in any desired color or shade according to the taste of the wearer. The insert, if

one be used, shall preferably be of the same color as the other material of the strap.

It will be understood that my invention is not limited to a shoulder strap having the 60 pile fabric innermost, that is, next to the skin of the wearer or some intermediate layer of clothing. If desired, the pile surface may be on the outer side of the strap, and in this case the strap will be kept in place by the 65 action of the pile threads against the next outer layer of clothing.

When a very light weight pile fabric is used it may, in some instances, become desirable to supplement the inherent body and 70 firmness of the fabric with some additional means. For example, the fabric may be impregnated or coated with a suitable chemical to give added stiffness and to render it less likely to wrinkle or crush.

75 It will thus be seen that my invention provides a shoulder strap which under normal conditions of wear will not become wrinkled or "stringy" in appearance and which inherently possesses means for resisting the troublesome tendency of such straps to slip down and off the shoulder.

The terms and expressions which I have employed are used as terms of description and not of limitation, and I have no intention, in the use of such terms and expressions of excluding any equivalents of the features shown and described, or portions thereof, but recognize that various modifications are possible within the scope of the invention claimed.

What I claim is:

1. A shoulder strap containing fabric which under normal conditions of wear will not readily wrinkle or become stringy, said 25 fabric having contact filaments adapted to engage the skin or clothing of the wearer, said filaments being inclined so that when the shoulder strap is in position on the wearer they point obliquely outward toward 100 the tip of the shoulder and downward toward the body.

2. A shoulder strap containing fabric having on at least one surface thereof contact filaments adapted to engage the skin or 105 clothing of the wearer, said filaments being inclined so that when the shoulder strap is in position on the wearer they point obliquely outward toward the tip of the shoulder and downward toward the body.

JOHN M. VAN HEUSEN.
